Fig. 2

To all whom it may concern:

Be it known that I, Fred M. Slavic, a citizen of the United States of America, residing at New Rochelle, county of Westchester, and State of New York, have invented a new, original, and ornamental Design for a Display Rack for Greeting Cards or Similar Article, of which the following is a specification, reference being had to the accompanying drawing, forming part thereof.

Figure 1 is a view in perspective of a display rack for greeting cards or similar article showing my new design.

Figure 2 is a top plan view.

The design rack for greeting cards presents a substantial identical appearance when viewed from the rear of Figure 1.

I claim:

The ornamental design for a display rack for greeting cards or similar article, as shown and described.
